UNITED STATES PATENT OFFICE.

THOMAS A. McCULLEY, OF SAN FRANCISCO, CALIFORNIA, ASSIGNOR OF FORTY-FIVE ONE-HUNDREDTHS TO MAUDE B. DEANE, OF SAN FRANCISCO, CALIFORNIA.

RAZOR-HONE.

1,393,297.

Specification of Letters Patent.

Patented Oct. 11, 1921.

Application filed August 16, 1920. Serial No. 403,938.

To all whom it may concern:

Be it known that I, THOMAS A. McCULLEY, a citizen of the United States, residing in the city and county of San Francisco and State of California, have invented a certain new and useful Improvement in Razor-Hones, of which the following is a specification.

My invention relates to improvements in razor hones and the like wherein a magnet is embedded in a composition stone to impart magnetic properties thereto.

The primary object of my invention is to provide an improved hone for razors and the like.

A further object is to provide a hone adapted to be magnetized by a permanent magnet therein.

A still further object is to provide a stone arranged to exert a magnetic attraction, whereby a razor or the like may be sharpened without application of pressure, thereby giving a uniform edge to the razor.

I accomplish these and other objects by means of the novel device disclosed in the drawings forming a part of the present specification, wherein like characters of reference are used to designate similar parts throughout said specification and drawings and in which—

Figure 1 is a plan view of my improved hone, the surface being partly broken away to disclose the magnet embedded therein.

Fig. 2 is a side elevation partly in section of the hone disclosed in Fig. 1.

Fig. 3 is an enlarged broken side elevation of the hone showing a razor as applied in sharpening.

In sharpening razors upon an ordinary hone, much care and skill is required to exert an even pressure to the blade such as will give uniform abrasion at the heel and toe of the blade, and prevent the forming of a feathered edge.

To overcome these difficulties I have invented my novel magnetic hone comprising a body portion 1 having smooth abrasive surfaces 2 on the top and bottom thereof for sharpening a razor 3 or other instruments requiring a keen cutting edge. The body 1 is formed by compressing an admixture of steel and an abrasive, such as corundum, emery or the like, into a suitable

mold under high pressure, the compression and binding of the material being carried out in the manner commonly followed in manufacturing composition stones of fine texture. A permanent horseshoe magnet 4 is embedded in the body in a position parallel to and approximately midway between the abrasive surfaces 2.

The steel and abrasive elements of the admixture from which the hone is formed are ground to an impalpable fineness and the proportion of steel in the admixture is such that particles of steel adjacent the magnet 4 will be magnetized by contact therewith, thereby becoming magnets capable of imparting magnetism to adjacent particles. In this manner the particles of steel throughout the stone become magnetized and each particle acts as an independent magnet in magnetizing adjacent particles and attracting external objects of a magnetic character. The particles of steel perform the additional function of retaining the magnetism of the magnet 4 by forming, in effect, a keeper between the poles of the magnet.

In use the razor or other instrument to be sharpened is applied to the hone in the usual manner and reciprocated with opposite sides of the cutting edge alternately contacting with the abrasive surface, but without application of downward pressure, the magnetic attraction exerted by the embedded magnet 4 through the medium of the magnetized particles of steel distributed throughout the hone being sufficient to cause the cutting edge to be firmly held against the abrasive surface. The attraction will be equal at all points along the edge of the razor and no skill will be required to prevent excessive abrasion at any one point. The formation of a feather edge due to excessive inclination of the blade or excessive pressure will also be eliminated as the razor will be attracted equally at the cutting edge and back thereby holding the razor flat against the hone as shown in Fig. 3 of the drawings.

The magnetic properties of my improved hone has the additional advantage of giving "life" to the razor, that is, giving a more smooth and even cutting edge due to the temporary magnetism imparted to the blade by contact with the stone, the ragged edge

observable through a microscope being caused to assume the erect position assumed by iron filings when attracted by a magnet.

As the details of construction of my improved magnetic hone are so susceptible to variation, I do not restrict myself to the precise arrangement disclosed in the drawings, but prefer to avail myself of such modifications as will fall within the scope of the appended claims.

Having thus described my invention what I claim as new and desire to secure by Letters Patent is:

1. A razor hone having an abrasive body; and a magnet embedded in said body.

2. A razor hone having a body comprising a composition of an abrasive and a magnetic substance; and a magnet embedded in said body.

THOMAS A. McCULLEY.
